UNITED STATES PATENT OFFICE

171,431

SLOT MACHINE BAR

Albert F. Villaudy, Los Angeles, Calif.

Application July 21, 1953, Serial No. 26,065

Term of patent 7 years

(Cl. D34—5)

To all whom it may concern:

Be it known that I, Albert F. Villaudy, a citizen of the United States of America, residing in the city of Los Angeles, in the county of Los Angeles, State of California, have invented a new, original, and ornamental Design for a Slot Machine Bar, of which the following is a specification, reference being had to the accompanying drawing forming a part thereof.

Figure 1 is a top plan view of a slot machine bar, showing my new design;

Figure 2 is a side elevational view thereof; and

Figure 3 is a fragmentary enlarged perspective view thereof.

I claim:

The ornamental design for a slot machine bar, substantially as shown and described.

ALBERT F. VILLAUDY.
